UNITED STATES PATENT OFFICE.

HORACE B. McCABE, OF LAKEWOOD, COLORADO.

ROCK-DRILL.

SPECIFICATION forming part of Letters Patent No. 548,324, dated October 22, 1895.

Application filed December 26, 1894. Serial No. 532,907. (No model.)

To all whom it may concern:

Be it known that I, HORACE B. McCABE, a citizen of the United States of America, residing at Lakewood, in the county of Jefferson 5 and State of Colorado, have invented certain new and useful Improvements in Rock-Drills; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 My invention relates to improvements in rock-drills; and it consists of the features, arrangements, and combinations hereinafter described and claimed, all of which will be fully understood by reference to the accompanying 20 drawings, in which is illustrated an embodiment thereof.

In the drawings, Figure 1 is a side elevation of my improved drill. Fig. 2 is a longitudinal section taken on the line C C, Fig. 1. Fig. 25 3 is a section taken on the line D D, Fig. 1. Fig. 4 is a section taken on the line V V, Figs. 1 and 2, looking toward the right. Fig. 5 is a section taken on the line Z Z, Figs. 1 and 2, looking toward the left. Fig. 6 is a section 30 taken on the line W W, Figs. 1 and 2. Fig. 7 is a section taken on the line i i, Fig. 8. Fig. 8 is a section taken on the line g g, Fig. 7. Fig. 9 is a section taken on the line h h, Figs. 1 and 2. Fig. 10 is an end elevation of the 35 drill shown in connection with the supporting-column. Fig. 11 is a section taken on the line B B, Fig. 10, looking toward the right, the parts being shown on a larger scale. Fig. 12 is a fragmentary longitudinal section of the 40 horizontal shaft attached to the column. Fig. 13 is a vertical section taken through the foot of the column. Fig. 14 is a section taken on the line A A, Fig. 13. Fig. 15 is a section taken through the tension-cap of the drill- 45 casing. Fig. 16 is a cross-section taken on the line S S, Fig. 15. Fig. 17 is a section taken on the line p p, Figs. 1 and 2.

Similar reference-characters indicating corresponding parts or elements in these views, 50 let the numeral 5 designate the drill-casing, having the base 5^a, fashioned to fit the track 6, having the toothed rack 6^a. The bottom

of this track is dovetailed to fit a socket 7^a of corresponding shape made in a cross-head 7^c, formed on one extremity of a horizontal 55 bar 7. This bar is hollow, and the opening therein registers with an opening in the cross-head extremity at right angles to the dovetailed socket 7^a. In this opening of the cross-head is inserted a keeper 8, having a socket 60 8^a, adapted to register with the socket 7^a. The keeper 8 has a threaded extremity protruding from the cross-head. The function of the keeper is to lock the track on the bar 7, and this is accomplished by applying a nut 65 to the threaded extremity of the keeper and screwing it to engagement with the cross-head. It is evident that the track may be securely locked on the bar in this manner.

The column 9 is provided with a base 9^a, 70 which is fastened to a foot-block 10 by a pin 12. In the base of this block is formed a socket, which receives a counterpart-lug 10^a, formed on the foot-block. The base of the column rests upon the lug 10^a of the foot-block, 75 while there is a space between the base of the block and the base of the column whereby the column may occupy a position inclined to the plane of the foot-block. The bottom of the foot-block is provided with ball-supports 10^c, 80 which engage sockets 10^a of the block.

To the column 9 is applied a two-part clamp 13, secured to the column by means of a screw inserted in coinciding threaded apertures formed in the lugs of the clamp parts. Formed 85 integral with one part of this clamp is a lug 14, having a clutch-face formed thereon to engage another similar face formed on a hanger 15, which is fastened to the lug by a screw 16. Upon the lower part of this hanger is formed 90 a bearing 15^a, adapted to engage the bar 7, which is fastened to the hanger by staples 17, having threaded extremities, to which nuts are applied. It will be readily observed that this mechanism for attaching the drill to the 95 column may be so regulated or adjusted as to give the drill any desired or necessary position.

Within the casing 5 of the drill is located the hammer composed of two independently-operated reciprocating parts 18 and 19, one being hollow and surrounding the other, which telescopes therein. The inner part 18 protrudes through the tension-cap 20 and is pro-

10,624
shoulder, which engages one extremity of its actuating-spring 21. This spring surrounds its hammer-part, and its rear extremity engages the tension-cap. The outer hammer part 19 is comparatively short. Its rear extremity bears against a spring 22, which surrounds the part 18, being located outside of the spring 21. These hammer parts are operated by cams 23 and 24, oppositely arranged on a shaft 25, to which they are made fast. This shaft is provided with a crank 26, employed in operating the machine. The curved faces of the cams engage lugs 18^a and 19^a, respectively. These lugs are made fast to or formed integral with the respective hammer parts and protrude through slots 5^c and 5^d, formed in the casing 5. The hammer parts 18 and 19 both strike against the head 27^a of the stem 27. To this stem is made fast the chuck 28, carrying the drill-bit 29. The bit is locked on the chuck by means of a key 30, made to fit a rectangular slot formed at right angles in the chuck.

auxiliary cam 43. The construction and arrangement of the parts must be such that the auxiliary cam acts on the rod 38 during the intervals between the hammer-strokes. It is evident that the rod must be released before the hammer parts are ready to strike.

Journaled in the base 5^a of the casing is a spindle 44, passing through a worm-block 45, 75 adapted to engage the toothed or cogged rack 6^a of the track. Made fast to one extremity of the block 45 is a ratchet-collar 46. The teeth of the collar are engaged by a dog 47, which is actuated by a lever 48, fulcrumed at 49. The opposite extremity of the lever is forked to engage a lug 38^a, carried by the reciprocating rod 38. As the rod 38 moves back and forth, the lever 48 will actuate the rod and the dog will impact the partial

requires that the power necessary for forcing the hammer against its spring be suddenly expended, otherwise one cam would catch the hammer before it was released by the other, 5 which of course would make the construction inoperative.

I do not limit my invention to the construction and arrangement of the hammer parts herein shown and described, as I am aware 10 that other forms may be employed without departing from the spirit of the invention.

The tension-cap 20 is provided with interiorly-projecting lugs 20^a, which engage slots 5^a, formed in the shell of the casing. The cap 15 is locked in place when properly adjusted by giving it a partial rotation, whereby the lugs 20^a are made to engage notches 5^b, formed along the edges of the slots and communicating therewith.

20 Having thus described my invention, what I claim is—

1. In a rock drill, the combination with the casing, the chuck, the bit and suitable operating cams, of a hammer comprising two independently operated parts, one being hollow and surrounding the other which telescopes therein, and both being always in line with the chuck stem, substantially as described.

2. In a rock drill, the combination with the 30 casing and operating cams, of the hammer comprising two independently operated parts, one being hollow and surrounding the other which telescopes therein and both operating on the same drill bit, substantially 35 as described.

3. In a rock drill, the hammer comprising two independently operated reciprocating parts, one being hollow and surrounding the other which telescopes therein, substantially 40 as described.

4. In a rock drill, the combination with the casing and operating cams, of a hammer comprising two independently operated, spring-

actuated parts, one being hollow and surrounding the other which telescopes therein, 45 substantially as described.

5. In a rock drill, the combination with the casing and operating cams, of a hammer comprising two independently operated parts, one being hollow and surrounding the other which 50 telescopes therein and a separate spring acting on each part, substantially as described.

6. In a rock drill, the combination with the casing, the track having the toothed rack, and the worm block journaled in the casing and 55 engaging the rack, of the auxiliary cam, the rod exteriorly mounted on the casing, a coil spring surrounding said rod which is provided with a lug lying in the path of the auxiliary cam, a ratchet collar made fast to one extremity of the worm block, a dog engaging the teeth of said collar, and a lever having one extremity engaging the dog, and the other extremity slotted to engage the lug on the rod, 60 substantially as described.

7. The combination with the drill of the upright column, the foot-block having a lug engaging a counterpart socket formed in the base of the column, a pin connecting the base of the column with the lug on the foot-block, 70 there being a space left between the bottom of the column and the base of the block, the clamp attached to the column, a hanger adjustably attached to the clamp, a bar clamped on the hanger, said bar being provided with 75 a socket adapted to receive the track of the drill, and a keeper attached to the bar for locking the drill on the bar, substantially as described.

In testimony whereof I affix my signature 80 in the presence of two witnesses.

HORACE B. McCABE.
